[57] CLAIM

The ornamental design for a tape dispenser, as shown and described.

DESCRIPTION

FIG. 1 is a right side elevational view of a tape dispenser showing my new design;
FIG. 2 is a front elevational view thereof;
FIG. 3 is a left side elevational view thereof;
FIG. 4 is a rear elevational view thereof;
FIG. 5 is a top plan view thereof;
FIG. 6 is a bottom plan view thereof;
FIG. 7 is a right front perspective view thereof;
FIG. 8 is a right rear perspective view thereof;
FIG. 9 is a right side elevational view of a second embodiment of my new design;
FIG. 10 is a front elevational view of FIG. 9;
FIG. 11 is a left side elevational view of FIG. 9;
FIG. 12 is a rear elevational view of FIG. 9;
FIG. 13 is a top plan view of FIG. 9;
FIG. 14 is a bottom plan view of FIG. 9;
FIG. 15 is a right front perspective view of FIG. 9; and
FIG. 16 is a right rear perspective view of FIG. 9.
